REFINER FOR PULP AND LIKE MATERIALS

William H. Cannard, Mosinee, Wis.

Application August 12, 1931, Serial No. 556,662

9 Claims. (Cl. 92—26)

This invention has reference to a crushing and grinding mill of the type known as the Jordan refiner which finds its chief use in the reduction of fibrous masses to pulp. It comprises a structure of such type which is extremely efficient and so designed that the crushing and grinding action thereof may be readily regulated and controlled to produce a milled product of any desired degree of refinement from relatively coarse to extremely fine.

To those skilled in the art of paper manufacture, the Jordan pulp refiner is well known. Essentially it comprises a tubular shell or casing having an inlet and outlet located at the respective ends and being provided with a power-driven rotor of a size such that its outer periphery is in close proximity to the inner periphery of the shell. Mounted circumferentially of the rotor are suitable blades which coact with the inner surface of the casing to mill material such as wood fiber fed into the space between the casing and rotor through the inlet. With a continuous feed the material, as it is milled, is whirled around in the shell and gradually moves towards the outlet.

The object of the present invention is to provide an alteration in the construction of the rotor and novel readily replaceable crushing and grinding instrumentalities with the view of greatly increasing the efficiency of the device and an automatic regulation of the milling action, in accordance with the material to be refined and the degree of fineness required, by varying the speed of the rotor. A structure having such characteristics constitutes an important advance over prior art structures which were not readily adaptable to operate on different types of materials and which could not be made to produce different degrees of refinement without considerable adjustment or substitution of parts.

To attain the desired object, I provide a series of milling rolls or rods seating in suitable grinding grooves or channels in the periphery of the rotor which crush the material to be treated against the inner wall of the casing, said rolls being unconnected with the rotor so as to float and move outwardly from their seats under centrifugal force to exert a varying crushing and grinding pressure in accordance with the speed of the rotor. The greater the speed the greater will be the centrifugal force urging the rolls outwardly towards the casing. Such rolls may be readily replaced without difficulty; if a true crushing action is desired plain rolls should be used, and if a grinding or cutting is desired in addition

to or in lieu of crushing fluted rolls may be substituted.

Preferably the casing is of gradually increasing diameter from the inlet to the outlet end and the rotor and grinding rolls are of tapering construction in conformity therewith, so as to facilitate the feed of material towards the outlet. Such arrangement further serves to cause the material to be whirled around the casing in a gradual spiral path, thus insuring thorough reduction and mixing before reaching the outlet. For greatest efficiency the rolls are relatively small and placed as close together as possible around the circumference of the rotor so as to present the greatest possible aggregate crushing or grinding surface.

With a refiner having the above-enumerated features, a tremendous grinding and crushing pressure may be obtained by utilizing a high speed driving instrumentality for the rotor, and such pressure may be reduced to a minimum or any intermediate degree merely by lowering the speed of the rotor to reduce the centrifugal force which controls the operation of the device.

Having now set forth the advantages of my invention and the features of construction giving rise thereto, I will now describe one practical embodiment shown in the accompanying drawings, which are only illustrative and, hence, not to be taken as limiting the invention to the details of construction therein disclosed.

Fig. 1 is a view in sectional elevation of a refiner embodying my invention;

Fig. 2 is a view taken on the line 2—2 of Fig. 1, showing the construction of the rotor and the milling rolls at the inlet end of the refiner;

Fig. 3 is a cross-sectional elevation corresponding to Fig. 2 and taken on the line 3—3 of Fig. 1 to show the construction of the rotor at the outlet end; and

Figs. 4 and 5 illustrate the construction of several forms of milling rolls which may be used.

Referring now to the drawings, the reference numeral 10 indicates a cylindrical shell or casing mounted on a base 11 by suitable means such as supports 12 and 13. Preferably, the casing 10 has an increasing diameter and is provided at its smaller extremity with an end plate 14 with which may be conveniently associated the supply inlet 15. A similar end plate 16 is provided at the other extremity of the casing, and an outlet 17, which, to insure the discharge of only properly refined material, should be located near the top of the casing, can be combined therewith. The end plates may be securely fastened to the casing by any suitable means such as bolts 18, 110

and strengthening ribs 19 may be located at suitable intervals circumferentially of the shell.

Extending axially through the casing 10 is a driving shaft 20 adapted to be connected by a key member 21 with a suitable power device and supported by suitable bearings 22 and 23, located at opposite ends of the casing. Associated with the respective end plates 14 and 16 are suitable stuffing boxes and glands 24 and 25 adapted to receive the driving shaft and prevent leakage therearound.

Located interiorly of the casing, which remains stationary on its base, is a rotor 40 which may well be hollow and provided with suitable supporting solid end plates 26 and 27 secured thereto by suitable bolts 28, said plates being secured to the driving shaft 20 by respective keys 29 and 30. The rotor is preferably of such length that the end plates thereof will be located in close proximity to the end walls 14 and 15 of the casing so that the material to be refined will be maintained between the outer and inner peripheries of the rotor and casing. The rotor should also have a gradually increasing diameter in conformity with that of the casing, the relation being such that there will be a comparatively small annular space between the two. In this connection it will be apparent that the end plate 27 will be of greater diameter than the opposite plate 26. To give the same adequate strength and rigidity they may be provided with relatively wide bushings surrounding the driving shaft and internal reinforcing ribs 31 and 32.

As above stated the end plates of the rotor are located in close proximity to the end walls of the casing, but the end plate 26 located adjacent the supply intake 15 is sufficiently spaced from wall 14 so that radially extending ribs 33 may be positioned on the outer side of the rotor plate, the purpose of the latter being to carry materials from the inlet to the space between the periphery of the rotor and casing.

The milling elements of my refiner comprise a series of rolls or rods 34 adapted to rotate and coat with the inner surface of the casing so that material will be crushed or ground therebetween. In order that the rolls may be revolved around the casing, the outer periphery of the rotor 40 is provided with a series of longitudinally extending grooves or channels 35 in which the rolls seat, as best shown in Figs. 2 and 3. As shown such channels have a curved cross-section extending up relatively steeply on one side and gradually on the other with the view of facilitating the outward movement of the rolls towards the casing under the influence of centrifugal force which acts on the rolls in accordance with the peripheral speed of the rotor, it being understood that the rolls are not secured to the rotor but merely "float" in the channels as the rotor revolves in the casing. The greater the speed and centrifugal force, the greater crushing or grinding pressure the rolls will exert on the materials located in the space adjacent the casing. As shown, the rolls should be relatively small and should for best operation be located as near together as practicable.

The several rolls may be provided with a round end 36 and the corresponding end plate of the rotor formed with suitable recesses 37 to receive the same and maintain the rolls in proper longitudinal alignment.

The rolls and channels therefor in the rotor should be of tapered construction in order that

the rolls coat with the inner surface of the tapered casing throughout substantially its entire length and facilitate the gradual feed of material as it is refined from the inlet 15 to the outlet 17. These features will be understood by a comparison of Figs. 2 and 3.

Where a crushing action, depending on the pressure developed, as distinguished from a grinding or cutting action is desired, smooth surfaced rolls such as shown in Fig. 1 should be used. However, for coarse material it is ordinarily necessary to produce grinding as well as crushing, and for this purpose a straight fluted roll, as shown in Fig. 4, or the spirally fluted roll of Fig. 5 may be readily substituted.

It will be understood that a structure embodying my invention takes full advantage of and, for best operation, is dependent upon centrifugal force created by rotation of the rotor, and that the effective milling or refining action thereof may be varied to a considerable degree merely by adjusting the speed of the rotor. The rolls and rotor may be readily replaced or modified, or equivalent milling elements substituted therefor. While the present invention is particularly adapted to use in refiners for fibrous materials, it will be understood that the same is capable of use for milling almost every kind of material.

I claim:

1. A refiner for pulp and similar materials comprising a tubular casing, a rotatable member therein, and milling rolls coating with the inner surface of the casing supported in longitudinal grooves on the periphery of the rotatable member, a solid end wall for the rotatable member having recesses in its inner face in alignment with the grooves, said milling rolls being rounded at one of their ends which seat in said recesses in the end of the rotating member to be maintained thereby in alignment longitudinally of the casing.

2. A refiner for pulp and like materials including a tubular casing, a rotor mounted therein with its periphery in spaced relation with the casing to provide an annular chamber for materials to be refined, longitudinal grooves in the periphery of the rotor carrying grinding elements adapted to operate in the annular chamber, an inlet for feeding material into one end of the casing, the rotor having a solid end plate adjacent said inlet and being provided with grooves in its peripheral edge registering with the grooves in the main portion of the rotor, said end plate being provided on its outer face with fins inclining away from the direction of rotation of the rotor adapted to feed material from the inlet outwardly to the grooves and the grinding chamber.

3. A refiner for pulp and similar materials comprising a tubular casing, a rotor mounted therein with its periphery in spaced relation with the casing to provide an annular chamber for materials to be refined, the rotor having a solid end located in spaced relation with the corresponding end of the casing, an inlet for feeding materials to said space, the periphery of the rotor having longitudinally extending grooves, grinding rollers operative in the annular chamber supported in said grooves and extending beyond the end of the rotor so as to overlie the space into which materials are fed.

4. A refiner for pulp and similar materials comprising a tubular casing, a rotor mounted therein with its periphery in spaced relation with the casing to provide an annular chamber for

- materials to be refined, the rotor having a solid end located in spaced relation with the corresponding end of the casing, an inlet for feeding materials to said space, the periphery of the rotor having longitudinally extending grooves, grinding rollers operative in the annular chamber supported in said grooves and extending beyond the end of the rotor so as to overlie the space into which materials are fed, the ends of the grinding rollers which overlie the space being supported by the end of the casing. 10
5. A refiner for pulp and similar materials comprising a tubular casing, a rotor mounted therein with its periphery in spaced relation with the casing to provide an annular chamber for materials to be refined, the rotor having a solid end located in spaced relation with the corresponding end of the casing, an inlet for feeding materials to said space, the periphery of the rotor having longitudinally extending grooves, grinding rollers operative in the annular chamber supported in said grooves and extending beyond the end of the rotor so as to overlie the space into which materials are fed, and ribs on the outer face of the end plate operating in the space between the end of the rotor and the end of the casing to feed materials outwardly to the grinding rollers. 20
6. A refiner for pulp and similar materials comprising a tubular casing, a rotor mounted therein with its periphery in spaced relation with the casing to provide an annular chamber for materials to be refined, longitudinal grooves in the periphery of the rotor adapted to carry grinding rollers, one end of the rotor closing the grooves at one end, the other end of the rotor having grooves registering with the longitudinal grooves, and grinding rollers carried in the 30
7. A refiner for pulp and like materials including a tubular casing, a rotor mounted therein, a series of milling rolls carried by the rotor in spaced relation with the inner surface of the casing and retaining grooves for said rolls on the rotor, said grooves each having a gradually sloping side wall adapted during rotation of the rotor to urge the milling rolls outwardly for co-action with the casing. 80
8. A refiner for pulp and like materials including a tubular casing, a rotor mounted therein, a series of milling rollers carried by the rotor in spaced relation with the inner surface of the casing and retaining grooves for said rollers on the periphery of the rotor, said grooves each having a gradually sloping side wall inclining away from the direction of rotation of the rotor adapted during rotation to force the milling rollers outwardly for coaction with the casing. 85
9. A refiner for pulp and similar materials comprising a tubular casing, a rotor mounted therein with its periphery in spaced relation with the casing to provide an annular chamber for materials to be refined, milling elements located in the annular chamber carried by the rotor to coact with the periphery of the casing, the rotor having an end wall located in spaced relation to one end of the casing to define a feed chamber, an inlet in the casing for supplying materials to said feed chamber, the ends of the milling elements extending beyond the ends of the rotor to overlie the feed chamber and initiate the grinding of the materials. 100
